UNITED STATES PATENT OFFICE

2,482,130

FLYING TARGET UNIT

Leslie A. Skinner, United States Army, Washington, D. C., assignor to the United States of America as represented by the Secretary of War

Application May 18, 1942, Serial No. 443,410

1 Claim. (Cl. 273—105.4)

(Granted under the act of March 3, 1883, as amended April 30, 1928; 370 O. G. 757)

1

The invention described herein may be manufactured and used by or for the Government for governmental purposes, without the payment to me of any royalty thereon.

This invention pertains to a target for practice in antiaircraft firing and more particularly to a rocket propelled target intended to simulate the flight of an airplane.

In conventional antiaircraft practice sleeve targets towed by airplanes and in some cases remotely controlled target airplanes have been employed. The first method has the obvious disadvantage that the towing plane is restricted to a fairly straight path and that the sleeve target will likewise follow a relatively straight and easily predictable path. The element of uncertainty essential to the usefulness of practice firing is entirely lacking. The second method mentioned above is impractical by reason of the expense of the equipment required and the probability of totally destroying the same in the event of a direct hit.

It is therefore an object of this invention to provide an antiaircraft target which by reason of the suddenness of its appearance and the character of its flight will furnish valuable practice for defense against low flying aircraft.

It is a further object to produce a flying target which is economical to produce, ship, and maintain, and one which has a maximum salvage value after use.

The exact nature of the invention as well as other objects and advantages thereof will clearly appear from a description of a preferred embodiment as shown in the accompanying drawing in which:

Figure 1 is a longitudinal sectional view of a target rocket constructed according to my invention.

Figure 2 is a cross sectional view on the line 2—2 of Fig. 1.

Figure 3 is a plan view of the charge supporting diaphragm.

Figure 4 is a cross sectional view on the line 4—4 of Fig. 3.

Figure 5 is a view similar to a portion of Fig. 1 showing a modified charge supporting and closure means.

Figure 6 is a plan view of the target base plate.

2 Figure 7 is an oblique view of the target plate securing means.

Figure 8 is a side elevational view partially in section showing a modified form of target rocket.

5 Figure 9 is a front end elevational view of the rocket closure shown in Fig. 8, the ogival plug being removed.

Figure 10 is an oblique view of the ogival plug.

Figure 11 is an end elevational view of the fin assembly.

10 Figure 12 is a view similar to Fig. 8 showing a modified form of target.

Figure 13 is a partial cross sectional view of one of the target plates of the Figure 12 rocket on the line 13—13 of Fig. 12.

15 Figure 14 is a longitudinal sectional view of a primer which might be used in any of the rockets.

Figure 15 is an enlarged longitudinal sectional view of the front end of the motor tube shown in Fig. 12.

20 Referring to the drawing by characters of reference, there is shown in Fig. 1 a rocket adapted to serve as an antiaircraft target. This rocket comprises three main units, a motor tube 1, a body tube 2, and a plurality of readily visible target plates 3. The motor tube 1 is formed with a suitably constricted portion 4 at its rear end and is flared outwardly therefrom to form a discharge nozzle 5. Contained within the motor tube 1 is a motor charge assembly comprising a charge supporting cage 6 and a plurality of axially perforated sticks 7 of charge composition secured thereon. The cage 6 may be formed by a plurality of headed rod members 8 welded or otherwise secured to a ring 9, or any of the charge supporting means shown in my copending applications.

25 Serial No. 411,512, filed September 19, 1941 (now Patent No. 2,446,560, issued May 12, 1948) may be used.

30 As shown in the drawing one of the charge units is slipped over each of the rod members and the head 10 of each of the rod members is engaged in one of the apertures 11 in the charge supporting diaphragm which comprises a pair of plates

35 12 and 13. In plate 12 a plurality of radial notches 11, have been formed in spaced relation about the circumference and are adapted to engage the shanks of the rod members. In the plate 13 registering apertures 11a of keyhole cross

40 section have been formed, the circular part of the

45 50

keyhole aperture being of sufficient diameter to admit the enlarged head 10 of the rod members 8 while the other portion will register with the notch 11 and, like that notch, will just pass the shank of the rod members 8. The plates may be secured to each other by spotwelding or other means to aid assembly, although such securing is not strictly necessary. The composite plate is assembled to the cage structure by engaging one of the rod members in each of the notches with the head of the rod member seated in the enlarged portion 11a.

The forward end of the motor tube 1 is provided with external threads 14 adapted to engage the internal threads 14a formed in the rear end of the body tube 2. A plate 15 has been welded or otherwise secured near the rear end of the body tube and the charge supporting plates are secured in the motor tube by clamping engagement between the front end face of the motor tube and the plate 15. The body tube 2 is extended forwardly a sufficient distance to insure stable flight and is provided with a counterbalance weight 16 secured in the front end thereof to also serve as a streamlined closure therefor.

An alternate method of joining the tubes and supporting the charge units is shown in Figure 5. In this modification the motor tube and body tube are joined substantially as before but no plate has been provided in the rear end of the body tube. A circumferential groove 17 has been provided near the front end of the motor tube, a cage supporting plate 18 similar to that previously discussed but of smaller diameter is received inside the motor tube, and a cup-like obturator 19 is received between the plate 18 and a plate 20. A spring snap ring 21 is engaged in the circumferential groove in front of the plates 18 and 20 and the assembly is clamped together by means of a bolt 22 threadably engaging the plate 18 and drawing a clamping bar 23 up against the forward edge of the spring snap ring.

The motor body is provided on its outer surface with a plurality of forwardly facing plate-engaging hooks or clips 24. Each group of hooks is spaced longitudinally of the motor tube in a straight line, a plane including all of the hooks of one line also including the axis of the tube. These lines of hooks are spaced equally about the circumference of the tube to provide for as many target plates as may be desired, four being shown in the drawing.

The target plates 3 are of generally semi-circular shape, each being formed from a pair of semi-circular plates of light sheet metal 25 and 26, each slightly dished and secured together about the circumference by means of a roll seam 27. Hair pin-like braces 28 of square steel bar stock are provided inside the target plates and secured thereto by spot welding or other similar means. A target base 29 shown separately in Figure 6 is inserted between the straight edges of the target plates and welded or otherwise secured thereto. The target base is provided with a series of symmetrically located D shaped apertures 30, a pair of such apertures being spaced apart by a bar 31 of unremoved metal adapted to be engaged by one of the target engaging hooks 24. As many pairs of such apertures are provided as there are hooks on the motor body and the bars 31 are spaced in the same relation as the hooks, being also symmetrically located with regard to the ends of the target base. It will be seen that the composite target plate may

be secured to the motor body simply by engaging one of the bars 31 beneath each hook 24 and sliding the target plate to the rear into contact with the base of the hooks. The symmetrical location of the hooks and apertures makes it immaterial which end of the target plate faces forwardly after application to the body.

One of the greatest advantages of this construction is that the rocket body and target plates may be shipped and stored separately in which condition they may be packed with maximum economy of space. Another advantage is that on impact with the ground after flight the damage may be localized as the target plates will be freed from the body and a maximum amount of material may be salvaged for reuse.

Figure 8 illustrates a modified form of target rocket which has certain advantages from the viewpoint of economy in construction. This 20 modification utilizes a motor tube 35 which is in general the same as that discussed in the previously described modification. In this type of construction the body tube and counterbalance weight are not needed as the target plates are secured about the rear end of the motor tube and extend rearwardly therefrom. The forward end of the motor tube may be closed as discussed in the previous modification although the closure shown in section in Fig. 8 and in end elevation in Fig. 9 is deemed preferable. This closure is similar to the modified form discussed in connection with Fig. 5 in that a circumferential groove 36 formed in the inner wall of the motor tube receives a spring snap ring 37. This snap ring 30 also engages a groove 38 formed in the outer wall of a charge supporting diaphragm 39 to which is secured the charge supporting plate 40 and cup-like obturator 41. The groove in the diaphragm is of sufficient depth to permit the snap ring 37 to be contracted thereinto and a cut-away portion 42 is provided to permit the in-turned ends 43 on the snap ring to be grasped with pliers or a similar device in effecting that purpose. When the charge has been secured to 45 the diaphragm the snap ring may be contracted and the assembly inserted into the motor tube until the snap ring can expand into the groove in the wall of the motor tube. As the groove 36 has less depth than the radial dimension of the 50 snap ring it will be evident that the diaphragm will then be securely held against longitudinal movement. An ogival plug 44, shown in Fig. 10, of wood or similar material has a portion 45 of reduced diameter adapted to be received in the 55 end of the motor tube and a further portion of reduced diameter adapted to be received within the end of the diaphragm 39. Grooves 46 have been provided to receive the in-turned portions 43 of the snap ring and a tongue 47 has 60 been provided for reception between those in-turned portions. It will be seen that when the ogive is in place it will be impossible for the snap ring to be contracted and hence the ogive assists in maintaining the closure. The ogive may be 65 conveniently secured in place by means of wood screws 48 penetrating the wall of the motor tube and engaging the ogival plug.

A plurality of equally spaced plate supporting tubes 49 have been welded or otherwise secured 70 to the exterior of the motor tube in axially parallel relation to the axis thereof. Each individual target plate comprises a tubular base 50 adapted to be closely received in one of the tubes 49 and provided with a plate 51 welded or otherwise 75 secured to the tube as best shown in the end eleva-

tion in Fig. 11. The base tube 50 is inserted in the supporting tube 49 in such a position that a radial line passing through the axis of the motor tube and of the base tube will be parallel to the plane of the target plate 51. Obviously the target plate might be secured to the base tube in such a manner as to depart radially therefrom rather than tangentially as shown in which case the plane of the plate should be radial with relation to the axis of the motor body. The base tube may be conveniently secured in place by means of a cotter 52 inserted through matching holes formed in the supporting tube and base tube. It is contemplated that the rear ends of the base tubes may be braced to each other by forming in the end of each tube a diametral slot 53 in which a brace ring 54 may be received and retained by cotters 55 passing through the base tube and the brace ring. In the event that further bracing of the target plates is needed it is contemplated that stabilizing braces 56 may be riveted in place between the plates.

It will be noted that this construction, while providing for target plates in the rear of the expansion nozzle, offers little or no obstruction to the proper expansion of the gas blast from the rocket nozzle.

Figure 12 shows another modification in target construction and attachment. The motor tube 60 is similar to the tube 35 in the Fig. 8 modification except for the omission of the target supporting tubes 49. A single target supporting tube 61 is received over the rear end of the motor tube 60 and secured thereto by brazing, welding, set screws or other equivalent means which will insure that the fin supporting tube forms a coaxial elongation of the motor tube. At spaced locations on the periphery of the supporting tube 61 plate engaging hooks 62 have been secured. These hooks are similar to and are located in similar manner to the hooks 24 on the motor tube 1 of the embodiment shown in Fig. 1. The target plates 3 of the Fig. 1 modification could be received on the hooks 62 but in the interest of manufacturing economy a modified plate 63 has been provided for this embodiment. This plate is shown in place in Fig. 12 and a cross sectional view of the plate alone is shown in Figure 13. The modified target plate 63 is made preferably of plywood or of some strong light weight composition product. The leading edge of the plate is provided with a fairing strip 64 which is bent back over the fin and tacked or riveted thereto. The use of such a fairing decreases the air resistance of the plate and serves to prevent any tendency of the composite material to split longitudinally under the effect of air pressure at high speeds as well as bracing the plate to the base structure. The base of the plate is secured in a channel 65 of substantially the cross section shown in Fig. 13 by rivets 66 which pass through both flanges of the channel and the plate. The widened base 67 of the channel is provided with a plurality of apertures 68 similar to the apertures 30 provided in the Figure 1 modification. A notch 69 has been provided in the plate in opposition to each aperture 68 to allow for the free reception of the hooks 62 which secure the plate to the body. The modified target plate is applied in the same manner as the plate of the Fig. 1 modification, previously discussed.

It is obvious that the manufacture of this latter modification is much simpler than that of the previously described modifications and that a considerable saving of material is effected. As

the target supporting tube is considerably larger than the expansion nozzle of the rocket little if any decrease in efficiency results from surrounding the expanding gases as they leave the nozzle.

Figure 15 shows a modification in the style of front end closure which provides for an electric primer adapted to ignite the rocket charge. The forward end of the motor tube 60 is provided with a portion of slightly reduced diameter and external threads 70 have been formed thereon. Engaging the threads 70 and securing a charge supporting diaphragm in a manner similar to that shown in Fig. 1 is a centrally apertured and cup-like cap 71. A tubular member 72 closed at one end and externally threaded at the other end is provided with a lock nut 73 and is passed through the central aperture in the cap into threaded engagement with an ogival nose weight 74. Insulating washers 75 and a bushing 76 of the same material electrically isolate the tubular member and ogival weight from the motor body and cap thereon. The tubular member is preferably provided with a plurality of flash holes 77 which may be conveniently sealed on the inside by a cylinder 78 of paper or other readily frangible or combustible material. The tubular member is substantially filled with an easily ignited charge 79 such as black powder and an electric squib 80 is surrounded thereby. One of the leads 81 from the squib is electrically connected to the ogival weight 74 and the other lead 82 is connected to the body cap 71. It will be readily apparent that the connection of a source of electric current between the ogival weight 74 and motor tube 60 will result in ignition of the squib and in communication of the ignition to the main driving charge. Obvious modifications will enable such a primer to be used with either of the other types of rocket body.

Figure 14 shows another form of primer unit which may be conveniently utilized to effect the ignition of the driving charge of any of the rockets discussed above. The primer comprises an electric squib or blasting charge igniter 83, which is supported by a disk 84. A container 85 is substantially filled with black powder 86 and is secured to the disk 84 by cementing or other convenient means with the powder 86 surrounding the charge igniter 83. A spacer stick 87 is secured to the disk 84 to locate the igniting charge well within the rocket body and a cork or plug 89 is provided on the stick to engage the nozzle and loosely retain the primer assembly in the rocket body. Electrical conductors 88 leading to the charge igniter 83 are secured to the spacer stick and passed through the plug 89 for connection to a battery or other source of current.

Obviously other modifications of the invention may be produced which will fall within the bounds of my invention as set forth by the appended claim.

I claim:

In a mobile target of the type comprising a rocket and wing members, the improvement comprising a hollow wing member of substantially triangular cross-section transversely of the rocket axis, a bi-lanceolate member of channel section fixedly nested in the base of the wing member to provide aerofoil sections parallel to the rocket axis, a tube surrounding the rocket and having outwardly struck portions, pairs of perforations in the bi-lanceolate member each defining a central web portion and each of said struck portions on the tube being received in one of the pairs of perforations and engaging the said web,

the perimeter of said wing being semi-circular with its diameter coinciding substantially with the rocket axis.

LESLIE A. SKINNER.
